CLAIM

The ornamental design for a connector as shown and described.

DESCRIPTION

FIG. 1 is a front top perspective view of a connector showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The uneven length broken lines immediately adjacent to the shaded areas define the bounds of the claimed design. The short dash-dash and long dash-dash even length broken lines depicting portions of the connector form no part of the claimed design. The connector is shown with a symbolic break in length and any portion between the brackets forms no part of the claimed design.
